UNITED STATES PATENT OFFICE.

ETHO HUSEL, OF COOPERSTOWN, NORTH DAKOTA.

GUARD-RAIL.

1,285,194.

Specification of Letters Patent. Patented Nov. 19, 1918.

Application filed June 5, 1918. Serial No. 238,312.

To all whom it may concern:

Be it known that I, ETHO HUSEL, a citizen of the United States, residing at Cooperstown, in the county of Griggs and State of North Dakota, have invented certain new and useful Improvements in Guard-Rails, of which the following is a specification.

The present invention relates to improvements in that type of protective devices used for the purpose of protecting pigs against injury by brood sows. It is a primary object of my invention to provide a device of this character which is easily attached in position within hog pens and capable of being adjusted to accord with the space allowable for its application in pens of different sizes.

To this end the invention consists of a sectional rail, bracket supporting means therefor, and means coöperating with the supporting means to prevent the accidental displacement of the rail from its support.

With the foregoing and other objects in view, the invention consists in the novel construction, combination and arrangement of parts to be hereinafter specifically described and claimed. Reference will now be had to the accompanying drawings forming a part of this specification, wherein.

Figure 1 is a side elevation of a device constructed in accordance with my invention;

Fig. 2 is a sectional view on the line 2—2 of Fig. 1; and

Figs. 3 and 4 are horizontal sectional views on the respective lines 3—3 and 4—4 of Fig. 1.

Throughout the following detail description and on the several figures of the drawings, similar parts are referred to by like reference characters.

Referring to the drawing, 1 indicates the lateral wall of a pig pen and 2, 2 brackets attached to said wall at the proper height, used for the purpose of supporting the adjustable

guard rail 3. This rail is preferably composed of telescoping sections 3', 3' each one of which at its outer extremity is provided with a head 4. The sections of the rail thus constructed and applied in position are held from displacement by adjustable collars 5, 50 one of such collars being provided for each section. Each collar carries a set screw 6 and when moved into position adjacent to an end bracket 2 it will prevent longitudinal movement of the rail in one direction while the heads 4 of said rail prevent movement thereof in the opposite direction. It will be apparent that the sections of the rail may be further telescoped one within the other to reduce the length of the rail or may be extended as the case may be for the purpose of lengthening the rail.

It is not unusual that when hogs are being fed, in their eagerness to obtain the food they mash small pigs against the pen walls, resulting in severe injury and death to the pigs. Where, however, the rail is used and adjusted at a suitable height from the ground floor the sows are prevented from jamming the pigs in the manner described, the latter taking positions beneath the rail which protects them. The article, it will be observed, is a simple one and has a wide range of adjustability for performing the usual function herein attributed to the device.

Having thus described my invention, what I claim as new is:

A guard device of the class described comprising a sectional telescopic rail, each section having a headed extremity, a series of 80 brackets in which said rail is journaled, and a set collar mounted upon each section for coöperation with the bracket supports at opposite sides to that occupied by the headed extremities.

In testimony whereof I affix my signature.

ETHO HUSEL.
